(57) CLAIM

The ornamental design for a combination shopping bag tote and organizer, as shown and described.

DESCRIPTION

FIG. 1 is a perspective view of a combination shopping bag tote and organizer, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, in an opened configuration to more clearly show the design of the combination shopping bag tote and organizer.

The hatching on the surface of the bag represents the material of the combination shopping bag tote and organizer and is shown fragmentally for convenience of illustration. The hatching is understood to be continuous over the surface of the combination shopping bag tote and organizer.
